UNITED STATES PATENT OFFICE.

THOMAS DONALD ADAIR, OF BOSTON, MASSACHUSETTS, ASSIGNOR TO STANDARD THERMOMETER COMPANY, OF PORTLAND, MAINE, A CORPORATION OF MAINE.

GASOLENE AND WATER SEPARATOR.

1,106,352.

Specification of Letters Patent. Patented Aug. 4, 1914.

Application filed December 4, 1913. Serial No. 804,623.

To all whom it may concern:

Be it known that I, THOMAS DONALD ADAIR, a citizen of the United States, residing at Dorchester, Boston, in the county of 5 Suffolk and State of Massachusetts, have invented certain new and useful Improvements in Gasolene and Water Separators; and I do hereby declare the following to be 10 a full, clear, and exact description of the invention, such as will enable others skilled in the art to which it appertains to make and use the same.

The present invention relates to an improvement in gasolene and water separators.

15 The object of the present invention is to produce an improved gasolene and water separator adapted for use in a gasolene supply pipe, which is simple and cheap in construction and efficient in operation.

20 To the above ends the present invention consists in the separator hereinafter described and particularly defined in the claim.

In the accompanying drawings illustrating the preferred embodiment of the invention, Figure 1 is a sectional elevation of 25 the separator; Fig. 2 is a top plan with the head removed; and Fig. 3 is a bottom plan.

The illustrated embodiment of the invention is described as follows:—The separator 30 in general consists of a cylindrical body having heads by which it is adapted to be attached to the inlet and outlet pipes, the gasolene flowing in at one end and out at the other, and the water carried with it being separated from the gasolene during its 35 passage through the device.

The body of the device consists of a tubular shell 1. This shell is closed at the lower end by the bottom 2 sweated in place, and 40 having a screw-threaded nipple 3 thereon adapted to receive the sleeve nut of the union by which it is attached to the gasolene supply pipe. The bottom is provided with three drain screws 4 having leather washers 5 under their heads to render them gasolene 45 tight. These screws screw into three holes in the bottom 2.

In assembling this separator with a carburetor or other apparatus, if only one drain 50 screw were provided it would sometimes happen to come in such a position as to be inaccessible, or accessible only with difficulty, so three screws are provided.

Rising from the bottom 2 is a delivery 55 pipe 10 which is driven with a drive fit

into the bottom, and at its upper end is provided with a deflector 11 which rises from one side of the delivery pipe 10 and extends transversely across and beyond the mouth of the delivery pipe. When gasolene 60 containing water flows in through this pipe it strikes the baffle 11 and any entrained water or particles of water carried along with the gasolene which strikes the baffle is arrested in its movement thereby and permitted to fall through the body of gasolene 65 in the separator to the bottom of the separator. In this way the direct flow of gasolene from the delivery pipe to the outlet is prevented, and the water is permitted the opportunity to separate itself from the moving gasolene and to drop out of the current thereof. The top 12 of the separator consists of a conical head which is adapted to be forced into the upper end of the cylindrical shell of the body 1 of the separator and 70 to be sweated into place. The upper end of the head forms a union to screw on to a threaded pipe connection similar to 3, to which gasolene is delivered from the separator. In the neck of the head 12 a fine wire 75 gauze diaphragm 13 is provided which is held against a shoulder by the follower 14 which is forced with a driving fit against the inside of the wire netting 13. This wire 80 netting affords a further preventive for the escape of water from the separator.

It will be observed that the mouth of the delivery pipe 10 is located at a considerable distance above the bottom of the separator, 85 so therefore a large quantity of water may collect in the separator without bringing it to such a level as to make its escape from the separator possible. In use, a drain screw 4 will be opened from time to time to draw 90 off any water which may have collected in the separator. In the preferred construction the delivery pipe is arranged vertically so that when the water contained in the gasolene strikes the baffle 11 its movement in the 95 direction of the gasolene flow is arrested and is permitted to fall away from such baffle at right angles to the baffle. This is desirable because it prevents the water from remaining in the stream of flowing gasolene 100 which otherwise might from time to time carry along some water with it. But while the preferred embodiment demands a vertical delivery pipe with a horizontal baffle, the invention, viewed in its broader aspects, con- 105

templates a delivery pipe entering a separating chamber provided near its mouth with a baffle arranged at right angles to the direction of the delivery pipe. Thus, viewed in 5 its broader aspects, the invention contemplates the use of the separator in horizontal position or in any position between the vertical and the horizontal.

The present invention is not limited to the 10 illustrated embodiment, as it may be embodied in other forms within the scope of the following claim.

I claim:

A gasolene and water separator consisting 15 of a body having a bottom provided with

an integral gasoline inlet, a delivery pipe supported inside the inlet and extending upward from the bottom and having a mouth at some elevation thereabove provided with a portion bent at right angles to 20 the direction of the delivery pipe to form a baffle extending across and covering but not closing the mouth of the delivery pipe, and a top having a discharge opening for the gasoline, substantially as described.

THOMAS DONALD ADAIR.
